UNITED STATES PATENT OFFICE.

HAROLD BLYE, OF GRAND RAPIDS, MICHIGAN, ASSIGNOR TO NATIONAL BRASS COMPANY, OF GRAND RAPIDS, MICHIGAN, A CORPORATION OF MICHIGAN.

LATCH SET.

1,327,695.

Specification of Letters Patent. Patented Jan. 13, 1920.

Application filed January 13, 1919. Serial No. 270,935.

To all whom it may concern:

Be it known that I, HAROLD BLYE, a citizen of the United States of America, residing at Grand Rapids, in the county of Kent 5 and State of Michigan, have invented certain new and useful Improvements in Latch Sets; and I do hereby declare the following to be a full, clear, and exact description of the invention, such as will enable others 10 skilled in the art to which it appertains to make and use the same.

This invention relates to a latch set particularly adapted for installation on swinging doors, such as those of a house or other 15 building used for dwelling purposes, though the latch set is not in any sense restricted to the one application. It is a primary object and purpose of the invention to provide a device of this character which can be readily 20 applied to doors by practically unskilled labor, where, heretofore, it has been common to use a latch which required the mortising of a hole rectangular in cross section and of 25 relatively large size, this necessitating the employment of skilled wood workers to make a proper installation of the latch set, my invention requiring that one hole be bored with a bit or auger which receives the 30 complete latch set for the installation. A further object of the invention is to produce a very simple and compact construction which can be manufactured at very low cost and one in which the parts going to make up 35 the device may be very readily disassembled to replace or otherwise repair any part which may become broken or out of working order. All of these objects and purposes together with novel constructions and 40 arrangements of parts to effect the same, as well as many others not at this time particularly noted, will appear fully and in detail 45 as the description progresses, reference being had to the accompanying drawing in which a preferred construction is illustrated, and in which,

Figure 1 is a partial plan and sectional view of a latch set applied to a door, the door, parts of the door knobs and escutcheons being shown in horizontal section and 50 the latch set in plan.

Fig. 2 is a side elevation of the latch set, one of the housing members being removed to show the interior latch mechanism.

Fig. 3 is a side elevation of the operating member of the latch, and

Fig. 4 is a rear view of a face plate and attached sleeve forming one element of the latch set construction.

Like reference characters refer to like parts in the different views of the drawings.

The latch set is adapted to be applied at the free vertical edge of a door 1, a cylindrical opening 2 being bored in said edge of the door to receive the latch. This latch set is also of cylindrical form, including in its construction two semi-cylindrical housing members 3 and 4 which placed together form a complete cylindrical housing. Each section or member 3 and 4 is provided at each end with a short pin 5 to pass in bayonet slots 6 cut in opposite sides of a rear cap 7 and a front sleeve 8, which sleeve is secured permanently to a face plate 9 lying against and, preferably, set in the vertical edge of the door. When thus attached together, a firm housing is made but one in which a very ready and rapid disassembly of the housing members may be had to get access to the inner mechanism of the latch should it ever become necessary to repair the same. The plate 9 has upper and lower holes 9^a through which screws are passed to attach it to the door, and is also formed with a central rectangular opening 10 for the passage of the latch bolt, the metal struck from the plate being turned to the rear inside of the sleeve 8 as indicated at 11, serving as a back against which the latch bolt may ride. The attachment of the sleeve 8 to the plate 9 may be in any suitable manner, though I prefer to extend lips or tangs from the sleeve through the plate and head the same over by riveting, this making a very firm and secure connection.

Within the cylindrical housing a member 12 is located formed from sheet metal and practically semi-cylindrical in form to fit against one of the housing members 4. At its outer end it is formed with a substantially circular end 13 in which a key-hole slot is cut. The latch bolt 14 is of conventional shape having one side beveled as at 15 to engage against the usual strike latch plate on the door casing. A rod 16 having oppositely flattened sides 16^a is connected to the rear of the bolt 14, passing through the slot

in the end 13 of the member 12 and formed with a head 17 back of said end 13, it being evident that the connection of the rod 16 to the end 13 may be made by entering the 5 rod into the key-hole slot with the flattened sides 16^a against the sides of the slot and then turning the rod after reaching the larger circular part of the slot, whereby disconnection of the rod from end 13 cannot 10 take place. A coiled spring 18 under compression is disposed between the part 14 and the end 13 normally serving to project the bolt through the opening 10. This spring is of comparatively light tension and on 15 closing the door yields readily to permit retraction of the bolt but returning the bolt to normal position as soon as free to do so.

The opposite end of the member 12 is formed with a substantially circular end 19 20 between which and the cap 7 a stronger coiled spring 20 is placed under compression to force the member 12 away from the cap. An operating rocker member 21 of cylindrical form is located in front of the 25 end 19 and is formed at each end with reduced extensions 21^a which are adapted to pass through and have bearing in suitable circular openings in the housing members 3 and 4, the member 12 being slotted at 22 to 30 pass said rocker member and permit movement of the member 12 lengthwise of the housing. At each side of the rocker member 20, the sides of the member 12 are formed with shoulders 23 and the member 20 has an 35 integral outwardly extending sector 24 against the edges of which shoulders 23 are pressed by the spring 20, it being evident that any rotation given to the rocker member about its axis serves to move the member 12 40 inwardly toward the cap 7 compressing spring 20 and at the same time retracting the bolt 14.

A squared opening 25 is made through and lengthwise of the rocker member 20 45 through which a rod square in cross section is inserted passing through suitable transverse openings in the door. This rod, indicated at 26, is threaded at its corners to screw into the shanks 27 of door knobs 28, 50 one being located at each side of the door and attached at each end of the rod 26, being threaded thereon as far as necessary to come close to the usual escutcheon plates 29 one of which is attached to each side of the door 55 and each of which has an opening to pass the rod 26. The knobs are held at any position to which they may be adjusted by set screws 30. The housing members 3 and 4 have parts cut away so as to provide a slot 60 31 in each side of the assembled housing, this permitting a larger sector 24 and a greater throw of the rocker member than if the same were restricted in size to the interior dimensions of the housing members 3 and 4.

65 This latch set may be made largely from

sheet metal and regular stock material, making the cost of manufacture very low. The parts are assembled without use of tools or machine work except for attachment of sleeve 8 to the plate 9. Should the springs become 70 broken or weaken after use, the latch set is disassembled instantly, the parts replaced and then reassembled very quickly without use of tools. This is also a very valuable asset to the structure in showing and explaining 75 the workings of the latch to customers. The bolt 14 rides against the in-turned tongue 11 which takes the pressure of the bolt received when the door is closed. But the greatest advantage consists in the 80 fact that to apply it to doors, only one opening has to be bored with one operation into the edge of the door and one transversely through the door, after which the latch set 85 may be inserted into the first opening, and the rod 26 through the transverse openings and through the rocker member, the escutcheons and knobs attached, this completing the installation with a minimum of expense for labor, and without danger of 90 improper mortising; while a lock set similarly housed within a cylindrical housing which I have in mind and which will form the subject matter of a future application for patent thereon may be installed in the door below 95 the latch set, the complete latch and lock being thus easily installed by merely boring the necessary holes to receive them without necessity of mortising a large rectangular opening to receive the combined latch and 100 lock for house doors as now commonly done.

I claim:

1. In a device of the character described, a face plate having an opening therethrough, a sleeve attached to the rear side of the plate 105 and provided with a bayonet slot therein, a cap similarly provided with a bayonet slot therein, a cylindrical housing formed of two semi-cylindrical parts disposed between the cap and sleeve and inserted at their ends 110 into the cap and sleeve, pins on said housing parts located in the slots, a latch bolt projecting partially through the opening in said face plate, means to retract the bolt into the housing, and spring means normally forcing the bolt partially out of the housing, substantially as described.

2. In a device of the character described, a housing comprising two semi-cylindrical parts, means for closing one end of the housing and detachably connecting the parts together at that end, means at the other end of the housing for similarly detachably connecting the parts together at that end, said means having an opening therethrough, a 120 latch bolt movably mounted inside of and normally partially projecting through the opening in said last mentioned means, means for manually retracting the latch bolt 125 entirely within the housing, and spring means 130

- normally projecting the bolt partially beyond the end of the housing.
3. In a device of the character described, an elongated cylindrical housing closed at 5 one end and having an opening at the opposite end, a latch bolt within the housing projecting partially through said opening, a member of semi-cylindrical form located within the housing and movable lengthwise 10 thereof, said member having circular ends, the one nearest the latch bolt having a slot therein, a rod attached to the bolt and passing through said slot, a head on the rod, a coiled spring around the rod between the 15 bolt and said member, a spring between the opposite end of the member and the closed end of the housing, and an operating rocker member mounted transversely of the housing against which said first member is 20 pressed by said last mentioned spring, said operating member when turned in either direction serving to move the first member and retract the latch bolt, substantially as described.
- 25 4. A construction containing the elements in combination claimed in claim 3, combined with means detachably passing through the rocker member for rotating it in either direction, substantially as described.
- 30 5. In a latch set, an elongated cylindrical housing, means to close one end of the housing, a sleeve into which the opposite end of the housing is inserted, a plate to which said sleeve is connected, said plate having an 35 opening therein with a part of the plate

turned back into the sleeve at one side of the opening, a latch bolt having a flat side riding against said turned back part of the plate and the opposite side beveled, said bolt normally projecting a short distance through 40 the opening in the plate beyond the housing, a member slidably mounted within the housing to move lengthwise thereof, connections between said member and bolt permitting inward movement of the bolt without moving said member, means normally yieldingly forcing the bolt outwardly located between the member and bolt, spring means between the member and the closed end of the housing normally forcing the member outwardly, 45 a rocker member rotatably mounted transversely of the housing and serving as a stop to outward movement of the member, said rocker member when rotated in either direction moving the member and attached bolt 50 inwardly, and means for turning the rocker member.

6. In a latch set, an elongated cylindrical housing, a plate attached to one end of the housing and provided with an inturned 60 tongue thereby forming an opening through the plate, a latch bolt having a flat side riding against said tongue and a beveled opposite side, means to normally project the bolt partially through the opening beyond 65 the end of the housing, and means for retracting the bolt entirely within the housing, substantially as described.

In testimony whereof I affix my signature.
HAROLD BLYE.
